MACHINE FOR CUTTING BOTTOM PIECES FOR PAPER CUPS.

1,124,516.

Specification of Letters Patent.

Patented Jan. 12, 1915.

Application filed August 30, 1913. Serial No. 787,408.

To all whom it may concern:

Be it known that we, HERBERT F. PROVANDIE and EDWIN H. WHITNEY, citizens of the United States, residing at Melrose and Rehoboth, respectively, in the counties of Middlesex and Bristol and State of Massachusetts, have invented an Improvement in Machines for Cutting Bottom Pieces for Paper Cups, of which the following is a specification.

This invention relates to a machine for cutting and flanging bottom-pieces for paper cups and other receptacles.

The machine embodying this invention involves taking a strip of paper from a roll and passing it between a pair of printing-rolls by which it is printed on one or-both sides, at regular intervals, and then passing it to a pair of feed-rolls which act to feed forward the strip, and in case it is required that the bottom-pieces shall have deposited upon them a small quantity of paraffin-wax the lower feed-roll is arranged in a reservoir containing liquid paraffin-wax, and upon rotation of said roll a thin layer is deposited on the under side of the strip. The strip then passes to another pair of feed-rolls, and between the two pairs of feed-rolls the strip may be reversed, if desired, to bring the paraffin-coated side up-
permost, and, in such case, reversing-means is arranged between said two pairs of feed-rolls. The strip then passes to a punch and die by which the bottom-pieces are cut from the strip and are forced down into and through the die; and associated with said punch and die is a flange-forming means through which the bottom-pieces are forced by a suitable plunger and marginal flanges formed on them. The waste portion of the strip from which the bottom-pieces have been cut passes between a pair of feed-rolls and by said rolls is fed forward in a direction away from the machine.

Figure 1 is a front elevation of the machine for cutting and flanging bottom-pieces embodying this invention. Fig. 2 is an enlarged plan view of the left-hand end-portion of the machine shown in Fig. 1. Fig. 3 is an enlarged plan view of the right-hand end-portion of the machine shown in Fig. 1, the punch and operating-means therefore being removed. Fig. 4 is an enlarged vertical section of the punch and die and flange-
device. Fig. 5 is a plan detail of the flanging-device. Fig. 6 is an enlarged view of intermittent actuating-means for the feeding-rolls. Fig. 7 is a detail of the clutch of the intermittent actuating-means. Fig. 8 is a detail of one pair of feed-rolls for the strip having means for effecting a quick adjustment of one of the rolls to move it into and out of engagement with the strip. Fig. 9 is a transverse vertical section of one pair of feed-rolls and reservoir adapted to contain liquid paraffin-wax in which the lower feed-roll of the pair rotates. Fig. 10 is a view of one of the bottom-pieces which is cut from the strip and has a marginal flange formed on it.

10 represents a strip of paper in the form of a roll which is of any suitable kind, quality and thickness, such for instance, as cardboard. Such a roll may be composed of numerous short pieces pasted or otherwise secured together. The strip 10 passes over suitable guides, as 12 and 13, to a rotary printing-device, here shown as a pair of printing-rolls 15, arranged horizontally one above the other and adapted to receive the strip between them, and to print upon one or both sides of the strip, as occasion may require. These printing-rolls are of any suitable construction, so far as this invention is concerned. The strip 10 then passes to a pair of feed-rolls 18, 19, arranged horizontally one above the other and geared together, and adapted to receive the strip between them and to feed it forward and also, as here shown, said feeding-rolls are employed to deposit on one side of the strip a thin layer of liquid paraffin-wax which subsequently solidifies thereon, and, for the accomplishment of this result, the lower feed-roll is employed as the roll to deposit the liquid paraffin-wax upon the strip. Said roll, therefore, is arranged to rotate in a reservoir 20 of any suitable shape and size, adapted to contain liquid paraffin-wax, there being a suitable heating-device arranged in said reservoir for maintaining the wax in liquid condition. A wiper 20 is pivotally supported at one side of the reservoir, which is held in yielding engagement with the roll 19, by means of a spring 23, thereby to regulate the quantity of liquid paraffin-wax which said roll shall deposit upon the strip. The strip then continues forward

and is reversed so that its waxed side is uppermost, and for the purpose of reversing it a standard 25 is erected on the frame having a vertical slot at its upper end which is made of a depth corresponding approximately to the width of the strip, and said slot receives the strip, which latter is deflected from a horizontal position to enter it, and permits the strip to be drawn there-through, whereupon it passes to horizontally arranged edge-guides 28, 29, located in front of a pair of horizontally arranged feed-rolls 30, 31. By means of the slotted standard the strip is deflected from the horizontal position to the vertical position and by means of the edge-guides is subsequently deflected from a vertical position to a horizontal position, so that while passing from the feed-rolls 18, 19, to the feed-rolls 30, 31, its position is reversed. In case it is not necessary to reverse the strip said reversing-means will be omitted.

Referring to Fig. 8 showing the second pair of feed-rolls 30, 31, it will be observed that a quick adjusting-means is provided for the upper roll 30, consisting of a hand-lever 32 connected to a coarse pitch adjusting-screw 33. Such adjustment is desirable in localizing the printing-strip with respect to the punch and die, to be hereafter described.

The strip 10 is fed forward by the feed-rolls 30, 31, to a punch and die by which bottom-pieces of any suitable size and shape, are cut therefrom, and said punch and die are or may be of any suitable construction, so far as this invention is concerned, and, as here shown, 35 represents the punch and 36 a stripper-plate and 37 a die-plate, which latter is located beneath the stripper-plate. Said punch is secured to the lower end of a vertically reciprocating sliding-form 40, which is operated by an eccentric 41 secured to a shaft 42.

Arranged beneath the punch and die is a flanging-device by which a marginal flange is formed on the bottom-piece, and, as here shown, said flanging-device consists of a flanging-ring 45, arranged beneath and concentric to the die, and a plurality of radially disposed fingers 46, are arranged beneath the flanging-ring which are yieldingly supported against outward radial movement by a spring 47, and a plunger 48 is arranged within and concentrically to the punch and of suitable shape and size to pass through the flanging-ring and yieldingly supported fingers and acts in coöperation therewith to turn up a flange on the edge of the bottom-pieces. The flanging-ring acts to form the flange, and the fingers respectively engage the numerous projections at the edge of the flange, and act to bend said projections inward, so that, the flange will be formed at a pronounced right angle, instead of being

allowed to bend backward owing to the resiliency of the paper. As the punch is reciprocated its operation is intermittent, and hence the strip 10 is fed forward intermittently, and, for the accomplishment of this result a cam 50 is secured to the shaft 42, which engages a pivoted lever 51, having connected therewith the upper end of a rod 52, having at its lower end a rack-bar 53, which engages a gear-wheel 54, loosely mounted to oscillate on a shaft 55, and said oscillating gear-wheel supports one or more pawls 56, which engages a ratchet-toothed wheel 57, secured to said shaft 55. The shaft 55 has a gear-wheel 60 secured to it which engages a pinion 61, which in turn engages a gear-wheel 62 on the lower feed-roll 31, thereby to intermittently drive said feed-roll. The shaft of the lower feed-roll 31 is extended forward and has secured to it a bevel-gear 65, which engages a bevel-gear 66, secured to a shaft 67, extended horizontally, lengthwise the machine-frame, and said bevel-gear shaft has secured to it a bevel-gear 70, which engages a bevel-gear 71, on the shaft of the upper feed-roll 18, thereby to intermittently rotate said feed-roll, and said forward gear-shaft also has secured to it another bevel-gear 75, which engages a bevel-gear 76, secured to the shaft 95 of the upper printing-roll 15, thereby to intermittently rotate said printing-roll. In lieu of the means here shown for intermittently rotating the several rolls any other means may be employed.

For the purpose of removing the waste portion of the strip 10 from the machine after the bottom-pieces have been cut therefrom a pair of horizontally arranged feed-rolls 80, 81, are located beyond the punch and die, which are geared together and one of which is adapted to be positively driven, and, as here shown, the upper feed-roll is positively yet intermittently driven like unto the aforesaid feed-rolls, and said upper feed-roll shaft has secured to it a gear-wheel 82, which is engaged by a gear-wheel 83, secured to a shaft 84, bearing a sprocket-wheel 85, over which a sprocket-chain 86 passes, which also passes over a sprocket-wheel 87 secured to the aforesaid shaft 55.

The bottom piece is shown at 87 in Fig. 10, the marginal flange being indicated at 88.

We claim:

1. A machine for cutting and flanging bottom pieces for paper receptacles and utilizing a strip of paper or the like, a printing device therefor, a cutting and punching device for coöperation with the strip, and means for manually controlling the feed of the strip to localize the printed portions thereof with respect to the cutting and punching device.

2. A machine for cutting and flanging bottom pieces for paper receptacles and utilizing a strip of paper or the like, a printing device for such paper strip, a cutting and flanging device coöperating with the strip, means controlled by the cutting and flanging device for normally imparting an intermittent feed to the strip, and manually operable means for varying the feed to localize the printed portions with respect to said cutting and flanging device. 5
3. In a machine for cutting and flanging bottom-pieces for paper cups, the combination of a reciprocating-punch, a stationary stripper-plate and a die-plate, a flanging-ring and a plurality of radially disposed yieldingly supported, fingers arranged below said flanging-ring and projecting inwardly beyond the inner edge of said ring, 10 and a concentrically disposed plunger, substantially as described. 15
4. In a machine for cutting and flanging bottom pieces for paper receptacles and utilizing a strip of paper or the like, a cutting and flanging device coöperating with the strip, coöperating feed rolls arranged adjacent the cutting and flanging device to receive the strip, means for the rapid adjustment of one of said rolls with respect to the other to control the feed of the strip 25 immediately to the cutting and flanging device, and intermittently operated means for said rolls controlled by the cutting and flanging device. 30

In testimony whereof, we have signed our names to this specification, in the presence of two subscribing witnesses.
